UNITED STATES PATENT OFFICE.

CHARLES H. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

ELECTRIC-LAMP MOUNTING.

Application filed June 12, 1924. Serial No. 719,536.

To all whom it may concern:

Be it known that I, CHARLES H. CUNO, a citizen of the United States of America, residing at Meriden, county of New Haven, 5 State of Connecticut, have invented new and useful Improvements in Electric-Lamp Mountings, of which the following is a specification.

My invention relates to a construction or 10 method of construction particularly useful as a trouble lamp attachment for automobiles. What are commonly termed electric cigar lighters are frequently provided or installed on automobiles. These devices are 15 of course in use only occasionally, although available whenever needed. Some cigar lighters employ a heating element which is removable or replaceable. The type of construction to which I refer will be found more 20 fully described and shown in United States Letters Patents No. 1,346,368 and No. 1,460,-095.

According to my present invention I have 25 provided a simple and inexpensive but durable lamp attachment which can be readily substituted for the heating unit of a cigar lighter. For economy in construction as well as accuracy in focusing and therefore maximum efficiency of light I prefer to construct the device of parts which are assembled in definite fixed relation by means of a simple form of jig.

Fig. 1 is a longitudinal cross sectional view showing an attachment embodying the 35 improvements of my invention.

Fig. 2 shows the three principal parts of the casing and indicating the method of assembly.

Fig. 3 shows a longitudinal section of a 40 modification.

The three principal parts of the preferred form are the tubular member 5, the body 6 and the reflector 7.

The tubular member contains in its inner 45 end an insulating piece 8 having a longitudinal passage for the sleeve 9 which contains a part of the plunger 10 and the spring 11 which presses the plunger outwardly. The shank of the tubular member 5 is provided with one or more projecting pins 12 adapted to engage in the bayonet slots of the socket of the cigar lighter or similar device (not shown). The outer end of the tubular member 5 is provided with one or 55 more, preferably two, bayonet slots 14

adapted to receive the pins 13 on the neck 14^a of an electric lamp bulb 15.

The body 6 is provided with a flange 16, in this instance turned inwardly, and soldered or otherwise suitably attached to the 60 tubular member 5.

The reflector 7 is provided with a flange 17 which is soldered or otherwise suitably secured to the outer edge of the body 6.

I also prefer to provide a glass 18 which 65 may conveniently be held in place by means of a split spring ring 19.

To secure the maximum brilliancy of illumination it is of course highly desirable that the filament 20 of the lamp bulb be located 70 at the focal center of the reflector 7. To insure this I prefer to assemble the parts of the casing of the attachment according to fixed plans and for that purpose I propose to employ a form of jig as diagrammatically 75 suggested in Fig. 2. It will be understood of course that the various parts of the casing or shell will be made of standard sizes. To assemble them in proper relative positions I provide a holder having a member 21 for 80 positioning the reflector, a shoulder such as 22 located in position to limit the insertion of the body 6 and a shoulder or abutment 23 to limit the insertion of the tubular member 5 to the proper distance so that when a 85 standard bulb is inserted in the socket of the tubular member 5 the filament 20 will be at the focal center of the reflector. This distance will be readily determined by experiment and fixed by the design of the jig. 90 When the parts are assembled in their proper positions they will be secured together by soldering, riveting or in any other suitable manner.

In the form shown in Fig. 3 the reflector 95 7' has a flange 16' which is secured directly to the tubular member 5 in such a position as to locate the bayonet slot 14 so as to bring the standard bulb filament at the focal center of the reflector.

I claim:

1. A lamp holder comprising a tubular body having an inwardly and reversely directed flange at one end, a reflector permanently secured to the other end, a tubular member permanently secured in said flange and having a socket with a bayonet slot at one end for receiving a lamp inserted in said reflector and having an external locking device at the rear end.

2. A lamp holder attachment comprising a tubular member having a socket in one end and adapted at its other end to be secured in a socket, an insulating member in the latter end, a spring pressed contact plunger therein, a body member having a reversely directed flange secured to said tubular member and a reflector secured to the opposite end of said body member.
- 10 3. A lamp holder attachment comprising a reflector having a reversely directed flange,

a tubular member secured in said flange, said tubular member having in its outer end a locking pin adapted to fit in the bayonet slot of a socket and having in its end within said reflector a bayonet slot adapted to receive the locking pin of a standard lamp bulb at the proper distance to locate the filament of the bulb approximately at the focal center of the reflector. 15

CHARLES H. CUNO.
